UNITED STATES PATENT OFFICE

CHAUNCEY MARSH GOODRICH, OF WINDSOR, ONTARIO, CANADA

SCAFFOLD

Application filed September 23, 1929. Serial No. 394,585.

This invention relates to scaffolds and, while not limited thereto, relates more particularly to suspension scaffolds for use in the erection of steel bridges, buildings and 5 the like, and has for its object the provision of such a scaffold which may be quickly assembled, may be readily moved from place to place, and will be materially safer than the rope-sling scaffolds generally used.

10 This scaffold may be readily suspended from the top or bottom chord of a bridge, or from any horizontal beam of the bridge or building structure, and, when desired, may be suspended from an inclined or curved beam.

Heretofore, in erecting steel structural work it has been customary for the steel workers or riveters to construct their own scaffolds from rope-slings and planking. These 20 rope sling scaffolds had a very narrow margin of safety at best, since the ropes may be insecurely tied, are readily weakened by wear, and may be burned by hot rivets.

Due to the narrow margin of safety in the 25 rope-sling scaffolds heretofore used, it has been necessary to frequently replace the ropes which is an item of considerable cost on a large structure. Another item of cost resulting from the use of the rope-sling scaffolds is the time consumed by the highly paid mechanics in constructing their own scaffolds.

The present invention overcomes all of the 35 above disadvantages of the rope-sling scaffold and greatly facilitates the work so as materially reduce the cost of erection.

In the drawings:

Figure 1 is a side elevation showing the scaffold of this invention suspended from a 40 horizontal beam or chord of a steel structure.

Figure 2 is a similar view showing the scaffold suspended from an inclined or curved beam or chord.

Figure 3 is an end elevation showing the 45 U-shaped end supporting members in detail.

Referring more particularly to the drawings, the numeral 2 designates a beam or chord of a steel structure upon which the scaffold is supported.

50 The scaffold comprises a pair of substan-

tially inverted U-shaped supporting members A and B.

The members A and B are of duplicate construction and comprise a suspension beam 3 adapted to extend transversely of and be supported on the beam 2 of the structure being erected. The beam 3 has a plurality of series of bolt receiving holes 4 along its length.

A pair of rigid scaffold supporting legs 5 are removably secured in spaced relation on the beam 3 at each side of the beam 2 and depend from the beam 3. The legs 5 are provided with a series of vertically spaced holes 6 and selected ones of the holes 6 are adapted to be registered with selected ones of the holes 4 in the beam 3 to receive attaching bolts. By bringing selected ones of the holes 6 into registration with selected ones of the holes 4 the legs 5 may be adjusted vertically and horizontally relative to the beam 3.

A plurality of platform supporting bars 7 are bridged across and removably bolted to the legs 5 in vertical spaced relation to each other. The bars 7 are provided with a series of horizontally spaced bolt holes 8 adjacent each end, and selected ones of the holes 8 are adapted to be brought to register with selected ones of the holes 6 in the legs 5 to receive the attaching bolts, thus providing for horizontal and vertical adjustment of the platform supporting bars.

A plurality of planks 9 are adapted to be supported on selected ones of the bars 7 and bridged between the U-shaped supporting members A and B, and other planks 10 are adapted to be bridged across the planks 9 thus forming a platform upon which workmen may stand to rivet or otherwise work on the steel beams being erected.

A hold-down or tie-bar 12 is bolted to the inner legs 5 of each pair of legs and extends under the structural beam 2 and parallel to the beam 3. The bar 12 is provided with a series of bolt holes 13 adjacent each end and selected ones of said holes are adapted to be brought into registry with selected ones of the holes 6 in the legs 5 to receive the securing bolts and thus adjust the bar to various sizes of beams 2.

The present scaffold is adapted to be suspended from horizontal, inclined or curved beams or chords 2 and, therefore, can be used wherever the ordinary rope-sling scaffolds are used.

5 In Figure 2 I have shown the scaffold applied to the curved or arched chord 2 of a bridge structure, with the platform bars 7 on the supporting member A arranged so that the second bar from the bottom is in alinement with the bottom bar on the member B for supporting the platform planks.

If desired, a suitable guard rail may be provided to prevent the workmen slipping 15 from the platform and when this is wanted suitable U-bolts 14 are provided in the legs 5 for holding pipe rails 15. If the pipe rails are not desired, suitable cables or chains may be secured to the U-bolts 14.

20 When it is necessary to relocate the scaffold the railing and planks are removed, the tie-bars 12 are removed, and the members A and B are then picked up bodily and moved to the new location where the scaffold may 25 be readily assembled. Experience has shown that two men can move and assemble scaffolds constructed like this invention for five riveting gangs, thus making a material saving in time lost by the skilled riveters, since otherwise said riveting gangs would have to spend considerable of their time assembling the scaffolds for use in their work.

While I have shown and described certain specific embodiments of my invention I do 35 not wish to be limited thereto, since various modifications may be made without departing from the scope thereof, as defined in the appended claims.

I claim:

40 1. A scaffold for use in the erection of steel bridges, buildings and the like, comprising a pair of substantially inverted U-shaped supporting members, each of said members comprising a suspension beam adapted to extend transversely of and be supported on a horizontal beam of the structure being erected, a pair of rigid scaffold legs removably secured in spaced relation adjacent each end of said beam, said legs being adjustable 45 vertically and horizontally relative to said beam, and a plurality of platform supporting bars bridged across and removably secured in vertically spaced relation to said legs, said bars being adjustable vertically and horizontally relative to said legs.

2. A scaffold for use in the erection of steel bridges, buildings and the like, comprising a pair of substantially inverted U-shaped supporting members, each of said members 60 comprising a suspension beam adapted to extend transversely of and be supported on a horizontal beam of the structure being erected, a pair of rigid scaffold legs removably secured in spaced relation adjacent each 65 end of said beam, said legs being adjustable

vertically and horizontally relative to said beam, a plurality of platform supporting bars bridged across and removably secured in vertically spaced relation to said legs, planking supported on said bars of said pair 70 of U-shaped supporting members forming a platform, and a tie-bar extending between the inner ones of said legs of each pair parallel with said suspension beam to prevent the tilting of said beam.

75 In testimony whereof, I have hereunto set my hand.

CHAUNCEY MARSH GOODRICH.
